METHOD OF COVERING ARTICLES

Lewis J. Bazzoni, Swampscott, Mass., assignor to
 United Shoe Machinery Corporation, Paterson,
 N. J., a corporation of New Jersey

Application September 22, 1933, Serial No. 690,604

10 Claims. (Cl. 41—10)

This invention relates to the manufacture of shoes and is illustrated with reference to a method of making decoratively covered heels.

It is sometimes customary to emboss a design upon a celluloid cover in order to produce a fancy heel or to simulate a leather-covered heel. A celluloid cover is sometimes applied to a wood heel blank by the use of a thick elastic pad, the cover being laid upon the pad and being wrapped around a clamped heel blank by hand or by the use of a machine.

Prior to applying the celluloid cover to the heel blank it is customary to bathe the cover in a softening solution until the cover is in a softened condition, the cover being applied to the heel in such condition and then being allowed to dry in order that it may acquire its original hardness. When it is desired to impart a design to a cover, it is common practice, after softening the cover, to subject the same to an embossing element, the embossed cover while in a softened condition being applied to the heel. When such a method is practiced the original design impressed upon the cover is distorted at various places due to the cover being stretched as it is applied to the heel blank.

In order to avoid the disadvantages of this old method and to speed up the manufacture of articles having embossed covers, there is provided, in accordance with the present invention, a method in which a cover of suitable sheet material capable of being softened is treated to render it soft and has an ornamental design formed upon its outside surface during its application to the blank to be covered while the cover is in softened condition. By practicing this method the embossing of the cover and the application of the cover to the blank take place at a single operation, and the design is embossed upon the cover without distortion. In the particular procedure which is described below the blank is a heel blank, and the cover is made of cellulosic material, such as celluloid, which may be softened by treatment with a suitable solvent.

Referring to the accompanying drawing where-in is illustrated a particular procedure—

Fig. 1 is a perspective view showing the relative positions of an elastic pad, a flexible matrix, a softened heel cover, and a heel blank preparatory to applying the cover to the blank and embossing the same;

Fig. 2 is an end elevation showing the resilient pad, the matrix, and the cover wrapped around the heel blank; and

Fig. 3 is a perspective view showing the covered and embossed heel.

The improved method may be performed by hand but is preferably carried out by the use of a machine. When the method is practiced by hand it is customary to secure a heel blank 10 in position by suitable clamping members (not shown) which operate against the attaching and top-lift-receiving faces 12 and 14, respectively, of the heel blank. The operator next lays a matrix 16, which consists of a flexible piece of cloth of the desired design and cut to the general shape of but larger than the outside face of the heel blank, upon a pad 18 made of sponge rubber or other suitable material. A cover 20 of cellulosic material, which has been previously softened by any suitable commercial softener, is then placed upon the matrix 16 and the operator wraps the pad 18 around the rear and side faces of the clamped heel blank 10, the edge portions of which have been covered with cement. During the wrapping and embossing operation the margins of the pad 18 overlap the breast, the attaching and the top-lift-receiving faces 22, 12, and 14, respectively, of the heel (Fig. 2) in order to inturn the margins 25 of the cover upon such faces. Since the margins of the pad 18 are forced around the edges of the heel blank 10, the margins of the cover 20 are inturned upon and are adhesively secured to the breast, the attaching and the top-lift-receiving 35 faces 22, 12, and 14, respectively.

As the cover is pulled around the heel blank 10 it is not only drawn tightly around the blank and cemented thereto but the design of the matrix 16 is embossed upon the cover. It will be noted 35 that because of the irregularity of the heel blank the cover is stretched at certain localities more than at others during the covering operation; and, if the cover is embossed to form a desired design before its application to the heel blank, it will not 40 have that design after its application to the blank. Moreover, the stretching of the cover as it is applied to the heel blank cannot be controlled so that the change in design during the covering operation may be compensated for. By 45 practicing the above method not only is an improved finished heel produced but the covering operation is expedited to a considerable extent.

After the cover 20 has been wrapped around the heel, as illustrated in Fig. 2, it is held in engagement with the heel blank for a few seconds to insure that the cement bond by which the cover is attached to the heel blank will set properly.

It requires considerable strength to draw the pad 18 together with the matrix 16 and the cover 55

20 around the heel blank since the pad is not only pulled around the heel blank with sufficient tension to emboss the design upon the cover but is also pulled around the breast, attaching and top-lift-receiving faces 22, 12, and 14, respectively, of the heel. Moreover, the ends of the pad 18 are pulled into close relationship with each other, as shown in Fig. 2, in order to cause the forward margins of the cover 20 to overlap the lateral breast portions of the heel blank. Accordingly, the heel may be covered by the use of a machine such for example as disclosed in United States Letters Patent No. 2,000,128, granted May 7, 1935 on an application filed in the name of William P. Devine.

Having described my invention, what I claim as new and desire to secure by Letters Patent of the United States is:

1. That method of making a decoratively covered article which comprises providing a cover of suitable sheet material which is capable of being softened and a blank to be covered, softening the cover and simultaneously applying the cover to a surface of the blank and forming upon the cover while it is in a softened condition an ornamental design which is different from the design of said surface of the blank.

2. That method of making a decoratively covered article which comprises providing a cover of suitable sheet material which is capable of being softened and a blank of irregular shape to be covered, softening the cover and simultaneously applying the cover to a surface of the blank and imparting to the outside base of the cover while it is in a softened condition an ornamental shape which is different from the shape of said surface of the blank.

3. That method of making a decoratively covered article which comprises, providing a cover of cellulosic material and a blank of irregular shape to be covered, softening the cover, and simultaneously applying the cover to a surface of the blank and forming upon the cover while the same is in a softened condition an ornamental design which is different from the design of said surface of the blank.

4. That method of making a decoratively covered article which comprises, providing a cover of cellulosic material and a blank of irregular shape to be covered, softening the cover, and applying the cover to a surface of the blank while the cover is in a softened condition and imparting to the cover while the same is in a softened condition upon the blank an ornamental shape which is different from the shape of said surface of the blank.

5. That method of making a decoratively cov-

ered heel which comprises, providing a cover of cellulosic material and a heel blank to be covered, softening the cover, and simultaneously applying the cover to a surface of the blank and forming upon the cover while the same is in a softened condition an ornamental design which is different from the design of said surface of the blank.

6. That method of making a decoratively covered heel which comprises, providing a cover of cellulosic material and a heel blank to be covered, softening the cover, and applying the cover to a surface of the blank while the cover is in a softened condition and imparting to the outside face of the cover while such cover is in a softened condition upon the heel blank an ornamental shape which is different from the shape of said surface of the blank.

7. That method of making a decoratively covered heel which comprises, providing a cover of cellulosic material and a heel blank to be covered, softening the cover, and applying the cover progressively to a surface of the blank while the cover is in a softened condition and progressively forming upon the cover while the same is in a softened condition upon the heel blank an ornamental design which is different from the design of the said surface of the blank.

8. That method of making a decoratively covered heel which comprises, providing a cover of cellulosic material and a heel blank to be covered, softening the cover, positioning the softened cover upon a flexible matrix, and causing the cover while in a softened condition to be applied to the blank under pressure of the matrix and at the same time to be embossed by said matrix.

9. That method of making a decoratively covered heel which comprises, providing a cover of cellulosic material and a heel blank to be covered, softening the cover, laying the softened cover upon a flexible matrix, and wrapping the matrix upon which the cover is positioned around the heel blank while the cover is in a softened condition in order to apply the cover to the heel blank and to emboss the same in accordance with the shape of the matrix.

10. That method of making a decoratively covered heel which comprises, providing a cover of cellulosic material and a heel blank to be covered, softening the cover, progressively conforming the softened cover to the heel blank, and forcing the same with considerable pressure against the heel blank to apply the cover securely to the heel blank and imparting an ornamental design to the outside face only of the softened cover during its application to the heel blank.

LEWIS J. BAZZONI.
